(57) **CLAIM**

The ornamental design for a plate for print head, as shown and described.

DESCRIPTION

FIG. 1 is a front view of a plate for print head;
FIG. 2 is a top view thereof;
FIG. 3 is an enlarged left side view thereof;
FIG. 4 is an enlarged right side view thereof;
FIG. 5 is a rear view thereof;
FIG. 6 is a bottom view thereof;
FIG. 7 is an enlarged partial top view thereof taken between lines 7—7 of FIG. 2; and,
FIG. 8 is an enlarged partial bottom view thereof.
The broken lines are for illustrative purposes only and form no part of the claimed design.
